UNITED STATES PATENT OFFICE.

PER HÅKANSSON, OF ESLÖF, SWEDEN.

ANTISEPTIC COMPOUND.

SPECIFICATION forming part of Letters Patent No. 580,213, dated April 6, 1897.

Application filed November 13, 1893. Serial No. 490,871. (No specimens.) Patented in Sweden October 1, 1892, No. 4,377; in France April 1, 1893, No. 229,107, and in Belgium April 8, 1893, No. 104,213.

To all whom it may concern:

Be it known that I, PER HÅKANSSON, a subject of the King of Sweden and Norway, residing in Eslöf, in the Kingdom of Sweden, have 5 invented certain new and useful Improvements in Antiseptic and Preserving Agents, (for which patents have been granted to me in Sweden, No. 4,377, dated October 1, 1892; in France, No. 229,107, dated April 1, 1893, and 10 in Belgium, No. 104,213, dated April 8, 1893,) of which the following is a specification.

My invention relates to antiseptic and preserving agents used for destroying micro-organisms, for neutralizing poisonous gases in 15 the air, for arresting putrefaction, for dressing wounds, &c., and as a remedy for cutaneous diseases, sores, and inflammation; and it consists of a liquid compound composed, essentially, of acetic ether, alcohol, and a comparatively small proportion of acetic acid. The compound may be mixed with water and have other ingredients added to it, according 20 to the uses to which it is to be applied, as will be hereinafter explained.

25 For most purposes, and particularly when the compound is to be used only for washing or for treatment of short duration, the compound may be in the following proportions: acetic ether, ten to forty per cent.; alcohol, twenty to fifty per cent.; acetic acid, two to 30 three per cent.

When the compound is intended to be used, by evaporating it, for purifying the air of 35 rooms, to preserve objects, or to arrest putrefaction, the compound may be used in a more concentrated form, as follows: acetic ether, sixty parts; alcohol, twenty to thirty parts; acetic acid, ten to twenty parts. This concentrated form of the compound is not, however, 40 ever, essential to good results.

Where the compound is to be used as a dressing for a considerable time, one part of the compound having the proportions first given above may be diluted with from one to 45 two parts of water.

Where the object to be preserved is submerged in the compound, the proportions and

strength of the compound must be varied somewhat to suit the kind of objects to be preserved and the mode of preservation. 50

Where the compound is to be used for purifying the air in rooms by evaporation or is used on the hair or person, perfumes may be added to it, and where its continued use on the skin renders the latter dry or harsh a little glycerin or some fat or oil may be added to the compound. If in its use color is likely to be affected by the acetic acid, the proportion of the latter may be reduced. 55

When acetic ether is added to alcohol or 60 to a mixture of alcohol and acetic acid, the effect is to produce a most powerful antiseptic and preserving agent, and yet one which contains no ingredient injurious or poisonous to man and which is not of itself injurious or 65 poisonous to man. This is important, as it renders the use of my compound safe even in careless hands, which is not the case with antiseptic agents which contain poisonous ingredients. "Poisonous" is here used in the 70 ordinary medical or chemical sense as indicating substances which if taken or inhaled in small quantities destroy human life.

While I have specified the preferred proportions of the ingredients I employ in the 75 compound, the really essential point in the proportions of such ingredients is that the acetic ether present shall be in quantity sufficient to cause the compound to act antiseptically. 80

Having thus described my invention, I claim—

An antiseptic and preserving agent composed of a compound of acetic ether and alcohol in substantially the proportions specified, 85 with a comparatively lesser percentage of acetic acid.

In witness whereof I have hereunto signed my name in the presence of two subscribing witnesses.

PER HÅKANSSON.
